UNITED STATES PATENT OFFICE.

DAVID LANG, OF BROOKLYN, NEW YORK.

CHILD'S GARMENT.

Application filed May 3, 1922. Serial No. 558,116.

To all whom it may concern:

Be it known that I, DAVID LANG, a citizen of the United States, and a resident of the city of New York, borough of Brooklyn, 5 in the county of Kings and State of New York, have invented a new and Improved Child's Garment, of which the following is a full, clear, and exact description.

This invention relates to a child's garment, and has for an object the provision 10 of a garment which to all appearances when in use is a single piece garment of the romper type, involving a dress or skirt portion to which a bloomer or pants portion 15 is detachably connected in a simple and efficient manner so that the pants portion can be very easily applied and removed.

Another object resides in the particular construction and arrangement of parts 20 which are hereinafter described and claimed, and shown in the accompanying drawings.

The invention is illustrated in the drawings, of which—

Figure 1 is a front view of the garment; 25 Fig. 2 is a rear view;

Fig. 3 is a section through a portion of the garment showing the particular manner in which the pants portion is fastened to the skirt portion; and

Fig. 4 shows the manner in which the pants portion can be opened at the side.

The form of the invention shown in the drawings is a preferred form, although it is understood that modifications in the construction and arrangement of the parts and in the character of the materials used may be adopted without departing from the spirit of the invention.

In accordance with the application of the 40 invention shown in the drawings, the garment comprises a waist 1 having a skirt portion 2. In Fig. 1 this skirt portion is shown upturned in order to disclose a relatively wide band 3. This band may be formed 45 from the material of the waist as a sort of hem or tuck, or may be made as a separate band and attached at its upper end to the inner face of the skirt portion at any desired distance above the lower edge thereof and 50 depending within the skirt portion. As shown in Fig. 3, for instance, the skirt por-

tion is turned back as at 4, shown in Fig. 3, to form a sort of hem, and the upper end of the band of material 3 is turned over and sewed between the upper end of the hem portion 5 and that portion of the skirt marked 6 in Fig. 3, the band and hem being secured to the skirt by the same stitching. This band portion 3 is provided throughout its length with a plurality of fastening devices 60 such as buttons 7. The pants portion 8 along its upper end is provided with a hem 9 having a plurality of buttonholes 10 therein adapted to engage with the buttons 7. As shown in Fig. 4, the pants portion at each 65 side thereof can be opened down the side in the usual manner.

In other words, the invention comprises a relatively wide band, hem or tuck formed on the inner face of the skirt portion of a 70 waist a suitable distance up beneath the lower edge thereof depending within the skirt portion. This band portion is provided with fastening devices, such as buttons, throughout its entire length, and these 75 are adapted to co-operate with fastening devices such as buttonholes on the upper edge of the pants portion so that the pants portion can be quickly and easily removed from the skirt portion but while fastened thereto the connection is hidden from view, so that the entire garment simulates the appearance of a onepiece garment. The waist portion can be, if desired, opened down the back, as shown in Fig. 2, part of the way. 85

What I claim is:

A child's garment comprising a waist portion having a skirt, the lower portion of said skirt folded upwardly within the skirt to form a tuck or hem extending entirely 90 around the skirt, a continuous band of material folded over at its upper end, said folded over end extending between the upper end of the tuck or hem and the inner face of the skirt, said folded over end and 95 tuck or hem permanently secured to the inner face of the skirt, and a plurality of fastening devices located on the outer side of said band adapted to removably secure a nether garment.

DAVID LANG.
